United States Patent [19]

Hollander et al.

US00D331909S

[11] Patent Number: Des. 331,909

[45] Date of Patent: ** Dec. 22, 1992

[54] ELECTRICAL CONNECTOR FOR
TEMPERATURE MEASURING EQUIPMENT

[75] Inventors: Milton B. Hollander, Stamford;
David R. Jacobs, Norwalk; William
E. McKinley, Stamford, all of Conn.

[73] Assignee: Omega Engineering, Inc., Stamford,
Conn.

[**] Term: 14 Years

[21] Appl. No.: 763,760

[22] Filed: Sep. 23, 1991

[52] U.S. Cl. D13/133

[58] Field of Search D13/133, 137, 138;
439/169, 219, 482, 502, 600, 620, 638, 692, 809,

[57] CLAIM

The ornamental design for a electrical connector for temperature measuring equipment, as shown and described.

DESCRIPTION

FIG. 1 is a left side elevational view of an electrical connector for temperature measuring equipment showing our new design. The broken line showing of the plug prongs and probe is included for the purpose of illustrating environmental elements only and forms no part of the design.

FIG. 2 is a front elevational view thereof;

FIG. 3 is a top plan view thereof;

FIG. 4 is a right side elevational view thereof; and,

FIG. 5 is a bottom plan view thereof.

FIG. 1

FIG. 2

FIG. 3

FIG. 4

FIG. 5
